AIR MOTOR

Earl W. Waterman, Coleville, Calif.

Application August 11, 1941, Serial No. 406,433

2 Claims. (Cl. 121—122)

My invention relates to new and useful improvements in air motors.

An important object of my invention is the provision of means for converting an internal combustion engine into an air motor, which means may be easily applied to the engine and requires that but slight changes be made in the engine to effect such conversion.

Still another object of my invention is the provision of means of the above mentioned character that may be easily assembled and applied to the engine and that is efficient and efficacious in the performance of its duties.

Other objects and advantages of my invention will be apparent during the course of the following description.

In the drawing, forming a part of this specification, and wherein like numerals are employed to designate like parts throughout the same.

Figure 1 is a side elevation of a device embodying my invention, parts being shown in elevation and parts in section for clearness of illustration.

Figure 2 is a vertical sectional view taken substantially on the line 2—2 of Figure 1, and

Figure 3 is an enlarged fragmentary vertical sectional view taken on the line 3—3 of Figure 1.

In the accompanying drawing, wherein for the purpose of illustration, is shown a preferred embodiment of my invention, the numeral 10 designates the block of an internal combustion engine. The block is provided with a pair of laterally spaced cylinders 11 and 12 the lower ends of which open into the crankcase 13 and the upper ends of which are closed by a cylinder head 14 in the conventional manner. A crank shaft 15 is mounted for rotation within the crankcase of the engine and the pistons 16 and 17 mounted for reciprocation within the cylinders are connected to the crank arms 18 and 19 of the crankshaft by means of the connecting rods 20 and 21. One end of the crankshaft extends exteriorly of the crankcase to receive the flywheel 22 and the opposite end thereof extends through the opposite end of the crankcase to receive the spur gear 23. A cam shaft 24 extends longitudinally through the crankcase above and at one side of the crankshaft and a timing gear 25 carried by one end thereof exteriorly of the casing meshes with the spur gear 23. The above construction is conventional in all internal combustion engines of this type.

In converting the engine into an air motor, I remove the intake manifold and close the openings 26 in the engine block by means of the plates 27 or the like. In addition to removing the intake manifold I remove the poppet valves which regulate the flow of fuel into the cylinders. When the fuel inlet valves have been removed it is necessary that some provision be made for closing

the fuel passages which lead from the valve seat to the cylinders. In Figure 2 I have illustrated the portion of the cylinder head overlying the valve seats 28 in which the fuel inlet valves were originally disposed as being devoid of the usual valve accommodating space. The object in reforming the underside of the cylinder head in this manner is to provide a plane surface which will close communication between the intake manifold and the cylinders. Obviously, this result may be accomplished in numerous ways, for instance, a gasket or the like could be inserted between the valve seats and the cylinder head to close the intake manifold; however I have found that the best results are obtained by filling the fuel inlet passages.

Air under pressure is injected into the working chambers 29 in the cylinder head through the valves 30. These valves are identical in their construction and a detailed description of but one will therefore be given. A sleeve 31 has the lower end thereof screw threaded into the spark plug opening 32 whereby the sleeve will rise vertically from the cylinder head to slidably support the collar 33 of the valve casing 34. The retaining ring 35 encloses the lower portion of the sleeve 31 and the base flanges 36 thereof seat against the upper surface of the cylinder head. Bolt elements 37 extend through the base flanges of the retaining ring and threaded into sockets 38 formed in the cylinder head to securely hold the ring associated therewith. The upstanding tubular portion of the retaining ring strengthens and supports the sleeve and the upper end 39 thereof provides a seat for limiting the downward sliding movement of the collar 33, which collar is normally held in vertically spaced relation with the seat 39 by means of a coil spring 40. The lower end of a tubular portion 41 is internally recessed as at 42 to receive the valve seat 43 and the portion thereof extending beyond the seat is screw threaded to receive the upper end of the collar 33. The valve seat extends transversely across the bore of the casing and supports the downwardly seating valve 44, the depending stem 45 of which extends through the seat to hold the enlarged head portion thereof in covering relation with the air inlet ports 46 in the seat. The upper end of the sleeve portion is closed by a plug member 47 and a coil spring 48 interposed between the plug and the head portion of the valve 44 normally holds the valve in the closed position. The stem portion 49 of an upwardly seating valve 50 extends through a central bore 51 provided in the valve plug 52 disposed in the upstanding sleeve 31. The stem portion 51 extends above the valve plug and in axial alignment with the valve stem 45 of the valve 44; however, as clearly illustrated in Figure 3 the valve stems of the respective valves are normal-

ly maintained in slightly spaced relation by the resilient action of the coil spring 40. The upwardly seating valve 50 is also provided with a depending shank 53 upon which the collar 54 is slidably mounted. The collar rests upon diametrically opposed lugs 55 extending into the bore of the sleeve and a coil spring 56 carried by the shank has the opposite ends thereof seating against the collar and valve 50 respectively to normally hold the valve in the closed position. An air inlet duct 57 extends through the wall of the tubular portion of the valve casing intermediate the plug 47 and the valve seat 43. The delivery tube of a pressure tank is connected in the duct 57 whereby air under pressure from the tank will have constant communication with the portion of the valve casing extending between the valve seat 43 and the plug member 47.

In order that the movements of the valve mechanisms 30 may be coordinated with the movements of the pistons 16 and 17, I have mounted a standard 58 on the cylinder head adjacent each of the valves and a rocker arm 59 is pivotally attached to each of the standards. One end of the rocker arm bears against the plug member 47 in the valve mechanism adjacent thereto and the opposite end of each of the rocker arms carries a composite push rod 60. The push rods extend downwardly through openings 61 provided in the cylinder head, through the inlet valve seats 28, through the intake manifold and through an opening 62 in the crankcase. The lower ends of the push rods are supported by the double lift cams 63 formed on the cam shaft 24. The timing gear 25 has a 2 to 1 ratio with the spur gear 23 of the crankshaft whereby the push rods will be reciprocated once during each rotation of the crankshaft. The push rods are yieldably held in pressed engagement with the cam shaft by means of the coil springs 64 so that the lower ends thereof will follow the peripheral surface of the cams at all times during their rotation.

The exhaust ports of the engine are opened and closed in the conventional manner by means of the poppet valves 65, the push rods 66 of which rest upon the cams 67 formed on the cam shaft, which last mentioned cams open the poppet valves 65 when the pistons are beginning their up-stroke and close the said valves when the pistons begin their downstroke. When the poppet valves 65 are open, air under pressure in the portion of the cylinder extending above the piston is permitted to egress through the exhaust manifold 68 and as soon as the pistons complete their up-stroke, the cams 63 operate to raise the push rods 60 to actuate the air inlet valve mechanisms 30.

As best illustrated in Figure 2, upward sliding movement of each of the lift rods 60 will raise the attached end of its respective rocker arm whereby to cause the opposite end of the rocker arm to press downwardly on the plug 47 of the inlet valve mechanism with which it is associated. Downward pressure of the rocker arm will cause the valve casing to slide downwardly on the sleeve 31 against the resilient action of the coil spring 40. The casing will slide downwardly on the sleeve a sufficient distance to effect engagement of the stem portions of the valves 44 and 50 whereby to effect simultaneous unseating of the valves. As soon as the downwardly seating valve 44 is opened air under pressure will pass

through the ports 46 and into the portion of the sleeve extending above the valve plug 52. Unseating of the valve 50 will permit the air to flow through the bore 51 in the valve plug and into the working chamber 29 of the cylinder to drive the piston downwardly. The cams 63 will hold the push rods 60 in the elevated position until the piston nears the end of its downstroke, at which time the cam will move to a position to permit the springs 40 and 64 to lower the push rod and close the inlet valve mechanism. When the piston begins its upstroke, the related cam 67 will open the poppet valve 65 to permit the air in the cylinder to discharge through the exhaust manifold 68.

It is to be understood that the pistons reciprocate alternately in the conventional manner so that one of the pistons is making its downstroke while the other of the pistons is making its upstroke.

The form of my invention herewith shown and described is to be taken as a preferred example of the same, and various changes in size, shape and arrangement of parts may be resorted to without departing from the spirit of my invention or the scope of the appended claims.

What I claim is:

1. In an air motor having a cylinder and a piston mounted for reciprocation within the cylinder to provide a working chamber therein, said chamber having an air inlet port, a valve mechanism for admitting air into the working chamber of the motor comprising a source of fluid pressure, a sleeve communicating with the air inlet port of the working chamber, a valve seat in the said sleeve, an upwardly seating valve having an upstanding stem portion disposed within the sleeve, spring means normally holding the valve against the said seat, a casing slidably mounted on the sleeve having an air inlet communicating with the source of fluid pressure, a valve seat in the casing below the said air inlet, a downwardly seating valve disposed within the casing, said valve having a depending stem portion engageable with the stem of the first mentioned valve, and spring means normally holding the second valve against the last mentioned seat, whereby shifting of the casing along the sleeve will move the valve stems into engagement with each other to effect simultaneous unseating of the said valves.

2. In an air motor, a cylinder, a slidable piston in the cylinder coacting therewith to provide a working chamber, said working chamber having an air inlet port, valve mechanism for admitting air into the working chamber comprising a source of fluid pressure, a sleeve communicating with the air inlet port, a valve seat in said sleeve, a first valve having a stem located in said sleeve, spring means normally holding said first valve against said seat, a casing slidably mounted on the sleeve having an air inlet communicating with the source of fluid pressure, a second valve seat in said casing, a second valve in said casing, said second valve having a stem engageable with said first mentioned stem, and spring means normally holding the second valve against said last mentioned seat, whereby shifting of the casing along the sleeve brings the valve stems into engagement one with the other to effect coacting unseating of the valves associated therewith.

EARL W. WATERMAN.
